UNITED STATES PATENT OFFICE.

THOMAS H. MACDONALD, OF BRIDGEPORT, CONNECTICUT, ASSIGNOR TO AMERICAN GRAPHOPHONE COMPANY, OF BRIDGEPORT, CONNECTICUT, A CORPORATION OF WEST VIRGINIA.

COMBINED DISPLAY DEVICE AND ANNOUNCING-GRAPHOPHONE.

1,119,295.

Specification of Letters Patent.

Patented Dec. 1, 1914.

Application filed August 26, 1910. Serial No. 579,172.

To all whom it may concern:

Be it known that I, THOMAS H. MACDONALD, of Bridgeport, Connecticut, have invented a new and useful Improvement in 5 Combined Display Devices and Announcing-Graphophones, which invention is fully set forth in the following specification.

The present invention is a combined display device and automatic announcing 10 graphophone, and its object is to provide means for simultaneously displaying cards, pictures or other devices addressed to the eye and at the same time making announcements from a graphophone of matter descriptive of or otherwise connected with the 15 devices displayed. Thus, for example, an advertising card may be displayed setting forth the merits of one class of goods and the talking machine may simultaneously 20 make announcements in connection therewith, after which the talking machine is silent and the display card is changed. Another card is automatically brought into view describing another class of goods, 25 whereupon the talking machine is again automatically set in operation and makes an appropriate announcement in connection with the second card; and so on through a series, the cards being automatically 30 turned into position to be again displayed in their turn and the talking record being automatically returned to its original position to repeat the operation after matter associated with the whole series of cards has been 35 produced.

One of the essential features in a device of this character is that the announcements from the talking machine should be so timed as to occur at the time when the appropriate 40 display card is in view, and one of the principal objects of the present invention is to provide means for thus timing the operation of the two devices, to the end that they may occur simultaneously.

With this object in view, the invention 45 consists of an intermittently operable display device and an intermittently operating talking machine, combined with a continuously moving timing device such, for example, as a timing shaft controlling, by suitable cams, the operation of the two devices, which continuously moving timing de-

vice is operatively connected both to the display device and to the talking machine. Any suitable construction of intermittently 55 operating talking machine may be employed and any suitable intermittently operable display device may be used. Preferably, I employ the intermittently operable talking machine shown, described and claimed in my 60 application Serial No. 466,680, filed December 9th, 1908, and an intermittently operable display device consisting of a series of display cards suspended in series by suitable wires connected to each card, which wires 65 rest on an inclined way or rails, the cards being one behind the other, so that only the front card is in view. The cards are held from falling off of the way or rails by a pair of pinions engaging the wires on the front 70 card, which pinions are controlled by an escapement, which is in turn controlled by a continuously driven timing shaft, which controls the intermittent operation of the talking machine by suitable cam mechanism, as 75 fully set forth in my aforesaid application. As the front card is released by the action of the escapement, it falls to the bottom of a suitable casing, thus permitting the next 80 card to the rear to come into view, and the fallen card is picked up by a continuously moving carrier by which it is again placed upon the rails to the rear of the series, to be again displayed when all of the cards in front of it have in turn been presented to 85 view.

The inventive idea is capable of receiving a variety of mechanical expressions, one of which, for the purpose of illustrating the invention, is shown in the accompanying drawings, in which—

Figure 1 is a plan view of an announcing graphophone, the same being that described and claimed in my aforesaid application Serial No. 466,680; Fig. 2 is a front view 95 of the display device associated with said announcing graphophone; Fig. 3 is a side view of said display device; Figs. 4 and 5 are details of the mechanism for feeding the display cards forward; and Figs. 6 and 7 100 are details of the escapement mechanism which controls the forward feed of said display cards.

Referring particularly to Fig. 1 of the

drawings, 1 and 2 indicate the usual end-
plates; 3, the main shaft with its mandrel 4
carrying an interchangeable record cylinder
5; 6, the reproducer carriage with its partial
5 nut 7 engaging the feed-screw 8. Suitable
trains of gearing are shown connecting shaft
3 with the feed-screw 8 and with the gov-
ernor (not shown). The motor (indicated
at 9, Fig. 2) is supposed to run continuously,
10 but the main shaft 3 and the other working
parts of the graphophone proper remain
stationary, except when a clutch is applied
to connect the main shaft with the driving
pulley 10, which latter is loose on the pro-
jecting end of the shaft 3 and driven from
15 the motor, as by a belt. This continuously
revolving pulley 10 carries on its hub the
pinion 11, which continuously drives the
train of gears that shifts the clutch referred
20 to, and from the same train is actuated the
mechanism for engaging (and disengaging)
the return screw and the graphophone car-
riage.

The left-hand end of the main shaft 3
25 is hollow, and in it is carried the stem 12
of the clutch head 13, the latter being lo-
cated beyond the pulley and having a ser-
rated face to engage counter-serrations on
the adjacent face of the head of pulley 10.
30 On the main shaft 3 is a shift collar 14 car-
rying a transverse pin 15 that passes
through longitudinal slots in the shaft 3,
and engages the stem 12. When this collar
35 is thrown to the left, the clutch is dis-
engaged, and the graphophone mechanism re-
mains idle, although the pulley 10 and its
train continue to revolve, but when collar
40 14 is shifted to the right, the clutch is en-
gaged and the driving pulley operates the
graphophone in the usual manner.

Preferably the mechanism for shifting
the announcing graphophone into and out
of operation is that described and claimed
in my aforesaid application, Serial No.
45 466,680, filed December 9th, 1908, wherein
the pulley pinion 11 drives the speed-re-
ducing train 16, 17 and 18. On the shaft
of gear 18 is a worm 19 in mesh with worm
gear 20 on the transverse shaft 21. It is
50 on this shaft 21, hereinafter called the
"timing shaft," that are mounted the sev-
eral cams that intermittently operate the
announcing graphophone and the display
device. The cams for shifting the announ-
55 cing graphophone into and out of operation
are indicated at 22 and 23, Fig. 1, and the
connections therebetween and the shift col-
lar 14 are the same as indicated in my said
application above referred to.

60 The reduction from pulley 10 to the
transverse timing shaft 21 and the cams
may be of any desired value. If a reduc-
tion of 400 is had, and the graphophone is
driven at the usual reproducing speed of
65 160 revolutions to the minute, it is evident

that the cams will make a complete revolu-
tion once in every $2\frac{1}{2}$ minutes, and that ac-
cordingly an announcement will be made
by the graphophone once in every $2\frac{1}{2}$ min-
utes. If the reduction is 320, and the
graphophone is driven at the same speed,
it is evident that the cams will make a com-
plete revolution once in every 2 minutes.
As fully set forth in my application above
referred to, the duration of the running of
the graphophone will be determined by the
relative positions of the seats in the two
cams 22 and 23, and by axially adjusting
cam 22, the duration of this audible repro-
duction can be nicely adjusted.

Each display card 24 is secured at its up-
per end to a wire 25, which latter projects
at each end beyond the sides of the card and
engages inclined ways or rails 26 suitably
mounted in the frame of the machine. 70
Preferably, these ways or rails are inclined
at an angle of about 20° . A rod 27 suit-
ably mounted in the frame of the machine
is provided with two pinions 28, the teeth
of which are of such pitch and size as to
mesh into the wires 25 as they lie on the way
or rails 26, as shown in Figs. 4 and 5. On
an extension of said rod 27 is a ratchet
wheel 29, more fully illustrated in Figs. 6
and 7. The rotation of this ratchet wheel
90 is controlled by an escapement mechanism
mounted on a rocker bar 30 which is sup-
ported by bearings 31 (Fig. 3). This rocker
bar 30 is rotated by arm 32, rod 33 attached
to the end of said arm, and crank 34
100 mounted on shaft 35. A tension spring 36
is secured at one extremity to the free end
of crank 34, and at the other extremity to
the base of the machine. Shaft 35 has also
mounted thereon a finger 37, which at its
105 free end engages the surface of cam 38
mounted upon the timing shaft 21. If the
reduction from the pulley 10 to the timing
shaft 21 is 400, said cam 38 will revolve
once every $2\frac{1}{2}$ minutes, and if the reduction
110 is 320, said cam 38 revolves once every 2
minutes. At the appropriate time point 39
of the cam passes the end of finger 37, and
the latter is elevated under the influence of
spring 36. At the same time, crank 34 and
115 rod 33 are depressed, which effects the rota-
tion of rocker arm 30, and accordingly op-
erates the escapement mechanism to rotate
pinions 28, to cause the card that has been
displayed to drop off the extremities of
120 ways or rails 26, and to bring the next suc-
ceeding card into display position.

The timing shaft 21 has mounted thereon
a gear wheel 40, which meshes with gear
41 carried on shaft 42, on which latter is
also mounted a sprocket pulley 43, around
which passes belt 44, which latter also en-
gages pulley 45 mounted on rod 46 suitably
supported in the framework of the ma-
chine. This belt is provided with hooks 47, 130

and these hooks engage the display card which has been dropped off the way or rails 26, and which has assumed the dotted line position (Fig. 3) on inclined surface 48. 5 A deflector 49 insures that the dropped display card will assume the proper position to be engaged by said hooks 47. When the belt 44 is rotated, the hooks engage the display card, and the latter is elevated to the 10 full-line position shown in Fig. 3, at which point disks 50 disengage said card from the hook and cause it to assume its position beyond the series of cards on the ways or rails 26. A spring 51 presses against the 15 lower part of the rearmost card and assists in this operation.

The escapement mechanism which operates the feed of the display cards comprises, preferably, a plate 52 mounted on rocker bar 20 30 provided with a tooth 53 and an abutment 54. On this plate 52 is pivoted a pawl 55, which is normally held against a pin 56 by the action of a spring 57. Under normal conditions, tooth 53 of the plate 52 engages one of the teeth of ratchet wheel 29, so that shaft 27 is prevented from rotating. When, however, finger 37 passes beyond point 39 of cam 38, the succeeding rotation 25 of rocker bar 30 removes said tooth 53 from the path of the teeth of ratchet wheel 29, and moves pawl 55 into engagement with said ratchet wheel 29. Spring 57 is not, however, strong enough to prevent movement of the display cards mounted on the 30 way or rails 26, and accordingly, under the action of gravity, said cards move forward, and pawl 55 is forced into engagement with the abutment 54 at the same time that one of the cards is forced off the way or rail 26, 35 and the succeeding card is presented at the display position. The continued rotation of cam 38 effects the depression of finger 37, the rotation of rocker bar 30, and the movement of tooth 53 back into the path of the 40 teeth of ratchet wheel 29; and rotation of said shaft 27 is again prevented until pawl 55 is once more moved into the path of ratchet wheel 29.

It will therefore be appreciated that, by 45 the provision of a timing device, such as timing shaft 21, which is common to both the intermittently-operating display device and the intermittently-operating announcing graphophone, and which controls the same through the action of cams 22, 23 and 38 50 mounted thereon—the announcements of the graphophone will be made at the appropriate time relative to the action of the display device; and the time of relative operation 55 of the display device and the announcing graphophone may be readily effected by proper change and adjustment of said cams.

What is claimed is:—

1. An intermittently operable display device, an intermittently operable talking ma-

chine, a continuously moving shaft, a cam thereon controlling the operation of said talking machine and a second cam thereon controlling the operation of said display device.

2. The combination of an inclined support, a series of display cards suspended from said support, an escapement operable to free said cards one at a time from said support, a continuously moving timing shaft 70 operatively connected to said escapement and intermittently releasing the same, and a continuously moving means for restoring said escaped cards to said support.

3. The combination of an inclined support, a series of display cards suspended on and movable by gravity along said support, a rotary escapement operable to free said cards one at a time from said support, a continuously moving timing shaft, a cam 80 mounted thereon intermittently releasing said escapement, and a continuously moving means for restoring said escaped cards.

4. The combination of an inclined support, a series of display cards suspended on 90 and movable by gravity along said support, a rotary escapement operable to free said cards one at a time from said support, a continuously moving timing shaft operatively connected to said escapement and intermittently releasing the same, a continuously 95 moving carrier for elevating said escaped cards, and means for removing said cards from said carrier onto said support.

5. The combination of an inclined support, a series of display cards on said support, an escapement operable to free said cards one at a time from said support, an inclined surface for receiving said escaped cards, a deflector associated therewith, a continuously moving timing shaft operatively 100 connected to said escapement and intermittently releasing the same, and a continuously moving means for restoring said escaped cards to said support.

6. The combination of an inclined support, a series of display cards fed along said support by gravity, a stop for said cards, a ratchet associated with said stop, a plate adapted to be engaged by said ratchet, 115 a pawl pivoted on said plate and yieldable in the direction of movement of said cards, means for moving said plate out of engagement with said ratchet and moving said pawl into engagement with said ratchet, and vice-versa, a card being fed from said support by gravity when said pawl is engaged by said ratchet.

7. The combination of an inclined support, a series of display cards fed along said support by gravity, a pinion engaging and stopping each card, a ratchet associated with said pinion, a plate movable axially of said ratchet, a spring-pressed pawl pivoted on said plate and yieldable in the direction of 125 130

movement of said cards, means for moving said plate out of engagement with said ratchet and moving said pawl into engagement with said ratchet, and vice-versa, a 5 card being fed from said support by gravity when said pawl is engaged by said ratchet.

In testimony whereof I have signed this

specification in the presence of two subscribing witnesses.

THOMAS H. MACDONALD.
